COMBINED DISPENSER FOR PACKETS OF COFFEE INGREDIENTS AND UNIT FOR SUPPLYING ELECTRICAL POWER TO BREW COFFEE, OR SIMILAR ARTICLE

Thomas F. Hines, 125 S. 3rd Ave., Arcadia, Calif.

Filed Feb. 5, 1962, Ser. No. 68,692

Term of patent 14 years

(Cl. D52—3)

Fig. 2

FIGURE 1 is a perspective view of a combined dispenser for packets of coffee ingredients and unit for supplying electrical power to brew coffee, or similar article, showing my new design;

FIGURE 2 is a top plan view thereof;

FIGURE 3 is a rear elevational view of the same; and

FIGURE 4 is an end elevational view, as seen from the right hand side of FIGURE 1.

I claim:

The ornamental design for a combined dispenser for

packets of coffee ingredients and unit for supplying electrical power to brew coffee, or similar article, substantially as shown.
